UNITED STATES PATENT OFFICE

150,286

DESIGN FOR A MUSICAL LAMP OR SIMILAR ARTICLE

Howard Asch, New York, N. Y.

Application June 13, 1946, Serial No. 130,676

Term of patent 3½ years

(Cl. D48—20)

To all whom it may concern:

Be it known that I, Howard Asch, a citizen of United States, residing at New York city, in the county of New York and State of New York, have invented a new, original, and ornamental Design for a Musical Lamp or Similar Article, of which the following is a specification, reference being had to the accompanying drawing, forming part thereof.

In the drawing

Fig. 1 is a top plan view of a musical lamp, showing my new design; and

Fig. 2 is a side elevational view thereof.

The rear of the lamp is substantially the same as the front, except as shown in the drawing.

I claim:

The ornamental design for a musical lamp or similar article, as shown and described.

HOWARD ASCH.
